UNITED STATES PATENT OFFICE.

LEWIS D. NELSON, OF COLDWATER, MICHIGAN, ASSIGNOR OF TWO-THIRDS TO ROBERT M. NEALE AND WILLIAM M. HATCH, BOTH OF UNION CITY, MICHIGAN.

FILLING MACHINE.

Application filed March 20, 1924. Serial No. 700,567.

To all whom it may concern:

Be it known that I, LEWIS D. NELSON, a citizen of the United States, residing at Coldwater, county of Branch, State of Michigan, have invented certain new and useful Improvements in Filling Machines, of which the following is a specification.

This invention relates to improvements in filling machines.

10 My improvements are especially designed by me for embodiment in bag filling machines for cement, plaster and the like and I have shown my improvements as I have embodied them in a bag filling machine, 15 although they are adapted for use in other relations.

The main objects of this invention are:

First, to provide an improved bag filling machine for heavy material such as cement 20 which is automatic in its operation.

Second, to provide an improved filling machine which is of very large capacity.

Third, to provide an improved filling machine having these advantages which is not 25 likely to get out of repair in use.

Objects pertaining to details and economies of construction and operation will definitely appear from the detailed description to follow.

30 I accomplish the objects of my invention by the devices and means described in the following specification. The invention is clearly defined and pointed out in the claims.

A structure which is a preferred embodiment 35 of my invention is clearly illustrated in the accompanying drawing forming a part of this application, in which:

Fig. I is a front elevation of a structure 40 embodying the features of my invention, a portion of the hopper and a portion of the base of the machine being broken away.

Fig. II is a side elevation looking from the right of Fig. I with portions of the hopper, base and discharge chute broken 45 away.

Fig. III is a front elevation corresponding to Fig. I with the parts in another position, the discharging movement having just taken place.

50 Fig. IV is a front elevation corresponding to Fig. III with the parts in another position.

Fig. V is a detail view mainly in vertical section on a line corresponding to line 5-5 55 of Figs. I and VI.

Fig. VI is a detail view mainly in vertical section on a line corresponding to line 6-6 of Fig. V.

Fig. VII is a detail view partially in section on a line corresponding to line 7-7 of Fig. V.

Fig. VIII is a plan view of the agitators.

In the drawing the sectional views are taken looking in the direction of the little arrows at the ends of the section lines and 65 similar numerals of reference refer to similar parts throughout the several views.

Referring to the drawing, I provide a frame consisting of a base 1 having a pedestal 2 mounted thereon carrying the hopper 3 and the ejector cylinder 4, this cylinder being connected to the bottom of the hopper by the chute or feed inlet extension 5 of the cylinder. The cylinder has a tangential discharge passage 6, see Fig. V. Within the 70 cylinder is a rotor or impeller designated generally by the numeral 7 and comprising a spider 8 having radial arms. For convenience in assembling the impeller is made up of sections as shown in Fig. V.

The cylinder wall is continued at 11 through the chute or passage 5 leading to the hopper but has side inlet openings 12 communicating with the hopper discharge.

This prevents the cement or other material 80 from falling directly upon the blades or its weight resting directly thereon, but allows it to flow in at the sides of the impeller in the quantities which the impeller is adapted to handle and prevents packing or clogging. 85 The rotor shaft 13 is driven from the belt 14 and the pulley 15 on the shaft 16.

Within the hopper I provide an agitator 90 comprising a vertical shaft 17 having a plurality of radial arms 18 disposed in spiral relation thereon, these arms being inclined forwardly so that when the agitator is rotated the arms tend to lift the material upwardly, at the same time stirring and agitating it so that it falls into the chute 100 5 by gravity only and is not packed therein, there being no tendency of the agitator to feed the material forwardly but merely to prevent its banking or clogging in the hopper and to insure that it is delivered to the ejecting rotor in the most desirable form for discharging from the cylinder into the bags.

The shaft 17 is supported by a bearing 110 bracket 19 arranged within the hopper, the

shaft 17 having a worm gear 20 thereon meshing with the driving worm 21 on the shaft 22. This shaft 22 is driven from a belt 23 and a pulley 24 on the shaft 16. 5 With this arrangement of parts the cement or like material is very rapidly discharged and at the same time the tendency to clog or pack or choke the cylinder is minimized.

The machine is designed to deliver into 10 "valve" bags which are slipped upon the spouts 25. One of the bags is indicated at 26. The spouts 25 are pivotally mounted at 27 on the carrier 28 which is in turn mounted on the scale beam 29 pivoted at 30 and 15 provided with a weight shown conventionally at 31. This spout carrier also serves the function of a valve for the discharge opening 6 of the ejector cylinder, the carrier having two openings 32 therein adapted to 20 alternately register with the opening 6 of the cylinder. The carrier being pivotally mounted upon the scale beam has an oscillating movement on its pivot and also an up and down movement on the scale beam, or 25 raises and lowers as the scale beam is actuated.

To automatically oscillate the member 28 I provide a yoke 33, the same being formed, 30 in the structure illustrated, in the upper end of the member 28 and an actuating lever 34 pivoted at 35 to engage this yoke, the lever being actuated by the spring 36 slidably engaging the slotted arm 37 on the upper end 35 of the lever. With the parts thus arranged, when the member 28 is raised the spring is placed under stress storing power for the actuating of the lever.

When the carrier is lowered as by the tilting of the scale beam under the weight of 40 a filled bag, the lever is swung by the spring to the opposite end of the yoke, thereby actuating the carrier. It is intended that the operator shall place a bag upon the spout, that is, in inoperative position, while a bag 45 is being filled so that as soon as the discharge passage of the ejector cylinder is uncovered the bag is placed to receive it. The spouts are automatically returned to their horizontal positions by the coiled springs 38 arranged on their pivots.

The spouts are supported in their horizontal position by the keeper arm 39 which projects through an opening 40 in the member 28 depending at the front thereof so 55 that the upwardly projecting arms 41 on the spouts swing under the keeper. When the carrier moves downwardly with the tilting of the scale beam these arms pass from under the keeper allowing the spout to tilt 60 under the weight of the filled bag and the bag to slip therefrom. The arm 39 is provided with a thrust bearing 42 under which the member 28 oscillates, the same serving as a lateral support.

I provide a platform 43 which is pivotal-

ly and slidably mounted at 44, the pivot rod engaging the vertical slot 45 in the supporting bracket 46 projecting from the pedestal 2. The platform is supported in its erected position by the latch 47 pivoted at 70 48 on the platform hanger or supporting yoke 49, this platform hanger being carried by the scale beam. The latch 47 is held in engagement with the pin 50 by means of the spring 51. On the downward movement of 75 the platform which occurs when the scale beam is actuated the latch 47 engages with the trip 52, thereby releasing the latch allowing the platform to tilt under the weight of the filled bag discharging the bag into 80 the chute 53. The platform is returned to its erected position by the weight 54 carried by the rearwardly projecting arm 55 on the platform. The pedestal has an opening 56 therein adapted to receive this weight. The 85 releasing of the spout and of the platform are timed so that they occur simultaneously, thus providing for the automatic discharge of the filled bags, it only being required that the operator shall place the bags upon the 90 spout while in inoperative position.

My improved filling machine is of large capacity, the labor required in operating the same being minimized. The machine is 95 not likely to become clogged as the material is delivered in a uniform condition as to compactness, the tendency to compact the material in the cylinder being minimized.

I have illustrated and described one practical embodiment of my invention. I have 100 not attempted to illustrate or describe other adaptations and modifications which I contemplate as I believe the disclosure made will enable those skilled in the art to embody or adapt my improvements as may be desired.

Having thus described my invention what I claim as new and desire to secure by Letters Patent is:

1. In a structure of the class described, the combination of a hopper, an ejector cylinder disposed so that a segmental portion of said cylinder projects into said hopper, the sides of said segmental portion being open providing side inlet openings, said cylinder having a tangentially disposed discharge opening, a rotor comprising a spider having radial blades mounted thereon and annular side members at the outer ends of said blades whereby the material to be ejected may pass laterally to said blades from said side openings of said cylinder, and an agitator disposed in said hopper above said cylinder and provided with forwardly inclined radial arms so that they tend to lift the material upwardly, the arms being spaced to permit the material to fall between them by gravity.

2. In a structure of the class described, the combination of a hopper, an ejector cylinder disposed so that a segmental portion of said

cylinder projects into said hopper, the sides of said segmental portion being open providing side inlet openings, said cylinder having a tangentially disposed discharge opening, and a rotor comprising a spider having radial blades mounted thereon and annular side members at the outer ends of said blades whereby the material to be ejected may pass laterally to said blades from 10 said side openings of said cylinder.

3. In a structure of the class described, the combination of a hopper, an ejector cylinder disposed so that a segmental portion of said cylinder projects into said hopper, the sides 15 of said segmental portion being open providing side inlet openings, said cylinder having a tangentially disposed discharge opening, a rotor open at its sides whereby the material to be ejected may pass laterally there- 20 to from said side openings of said cylinder, and an agitator disposed in said hopper above said cylinder and provided with forwardly inclined blades disposed so that they tend to lift the material upwardly while 25 permitting the material to fall between them by gravity.

4. In a structure of the class described, the combination of a hopper, an ejector cylinder disposed so that a segmental portion of said 30 cylinder projects into said hopper, the sides of said segmental portion being open providing side inlet openings, said cylinder having a tangentially disposed discharge opening, and a rotor open at its sides whereby

the material to be ejected may pass laterally 35 thereto from said side openings of said cylinder.

5. In a structure of the class described, the combination of a hopper, an ejector cylinder disposed below said hopper so that the material flows thereto by gravity, and an agitator disposed in said hopper above said cylinder and provided with forwardly inclined radial blades disposed so that they tend to lift the material upwardly, the arms being 45 spaced to permit the material to fall between them by gravity.

6. In a structure of the class described, the combination of a hopper, an ejector cylinder disposed below the hopper so that the material to be ejected passes thereto by gravity, and an agitator disposed in said hopper above said cylinder and acting to lift the material engaged thereby upwardly while permitting it to fall by gravity to said cylinder. 55

7. In a structure of the class described, the combination of a hopper, an ejector disposed below the hopper so that the material to be ejected passes thereto by gravity, and an agitator disposed in said hopper above said cylinder and acting to lift the material engaged thereby upwardly while permitting it to fall by gravity to said cylinder. 60

In witness whereof, I have hereunto set 65 my hand.

LEWIS D. NELSON.
